UNITED STATES PATENT OFFICE.

WILLIAM JOHN WHITING, OF HANDSWORTH, NEAR BIRMINGHAM, ENGLAND.

AUTOMATIC FIREARM.

939,882.

Specification of Letters Patent.

Patented Nov. 9, 1909.

Application filed April 9, 1909. Serial No. 488,917.

To all whom it may concern:

Be it known that I, WILLIAM JOHN WHITING, a subject of the King of Great Britain, residing at 111 Autrobus road, Handsworth, 5 near Birmingham, England, director of public company, have invented certain new and useful Improvements in Automatic Firearms, of which the following is a specification.

10 This invention has reference to automatic small arms of the type in which the barrel is fixed to the body or frame, and the breech-slide, which is externally mounted on said frame, is traversed rearwardly on each discharge, by the direct action of the recoil and returned immediately by the reaction or return spring while the hammer of the firing mechanism is arranged externally and behind the breech slide.

20 The object of the said invention is to provide an improved construction of small-arm of the above-mentioned type in which the reciprocating breech slide is combined with firing and safety mechanism that is so 25 arranged that it is impossible for the arm to be discharged unless the handle or stock is firmly gripped in the hand with the intention of firing a shot while when the handle is so grasped after the cocking of the 30 hammer (either by the recoil of the breech slide after the previous discharge or by hand) the arm is immediately and automatically made ready for firing and can be discharged by merely pulling the trigger.

35 Figures 1 to 15 of the accompanying drawings show an automatic pistol constructed in accordance with one form of my invention, wherein the trigger and sear of the firing mechanism are supported, at the rear 40 of the external breech-slide, in a spring-influenced housing or supplementary frame which is separate from the main frame that carries the trigger and sear-tripping bar and is mounted in the rear part of the handle 45 or grip in such a way that normally the hammer and sear are held out of range of the sear-tripping bar so that the pistol cannot be fired if the trigger is pulled, whereas when the handle is grasped for firing, an 50 operative relationship is automatically established between all the parts of the firing mechanism. Thus Fig. 1 is a partial longitudinal vertical section of the pistol, clearly showing the construction or arrange-

ment of the separate housing or mounting 55 which carries the sear and hammer of the firing mechanism. Fig. 2 is a similar view to Fig. 1, except that part of the housing is shown in section to illustrate more clearly the disposition or arrangement of the sear 60 and sear-spring and hammer and hammer spring, while the parts are shown in the positions which they are compelled to assume when the housing is moved by the hand gripping the pistol prior to firing. Fig. 3 65 is a horizontal section of the pistol taken on the dotted line α Fig. 1. Fig. 4 shows an elevation, partly in section, of a portion of the pistol, with the parts of the firing mechanism in the positions they assume when the 70 trigger is pulled. Fig. 5 shows the rear or handle portion of the frame of the pistol and the sear and hammer housing separated, or with the latter removed from the former 75 so as to illustrate how the said housing, with the hammer and sear, constitutes a complete or self-contained unit which is independent of and movable relative to the other parts of the pistol. Fig. 6 shows an edge view of the inner side of the housing element. Fig. 80 7 is a complete vertical section of the same and Fig. 8 is a top side plan thereof. Fig. 9 is a top side plan of the rear portion of the frame or body of the pistol and shows how the same is constructed to adapt it for the 85 reception of the housing element. Figs. 10 and 11 are detail views of the rear portion of the frame showing the same adapted to receive a slidable housing; Fig. 12 is a detail view of a safety housing adapted to be 90 slidably mounted in the frame when constructed as shown in Figs. 10 and 11; Figs. 13, 14 and 15 are detail fragmentary views of modified forms of the invention wherein the same spring which serves to hold the 95 safety housing in retracted or inoperative position may serve as a magazine latch.

The same letters of reference indicate corresponding parts in the said Figs. 1 to 15.

In the particular construction represented 100 in these figures, the trigger a is pivoted, in the usual manner, at the front of the frame or body b of the pistol, and is provided with an ordinary sear-operating bar or limb c but the part of the said body that comes behind the grip or handle is formed with a pair of cheeks or laterally-separated extensions b^1 , between which is mounted a hous-

ing or supplementary frame *d* that carries the sear and sear-spring *e*, *e*¹ and the hammer and hammer-spring *f*, *f*¹ of the firing mechanism, and is suitably pivoted to the 5 said main frame so that the whole of the parts *d*, *e*, *f* are capable of rocking bodily, or as a single self-contained unit, in the longer direction of the pistol. From the underside of the said housing, there depends a lever-like extension *d*¹ which is adapted to fit into the 10 suitable space or clearance *g* in the rear edge of the handle or grip of the pistol, and is acted upon by a spring *h* the tendency of which is to place the said housing in a position 15 wherein the sear *e* is quite out of range of the operating bar as shown in Fig. 1, and cannot, when the pistol is cocked, be tripped out of bent with the hammer, even should the trigger and sear-operating bar *a*, 20 *e*, be pressed back to the limit of their movement. Thus the arrangement affords an absolutely certain "safety" effect when the parts are so positioned by the spring. The said spring also tends to hold the lever-extension 25 of the rocking housing in a position in which the greater portion thereof projects to considerable extent beyond the back of the handle or grip as also shown in Figs. 1 and 2, so that when the latter is firmly 30 grasped in the hand, the pressure of the palm is exerted against the said lever and moves the same in the forward direction, in opposition to the spring. This movement also rocks or tilts the sear housing and 35 brings the sear into engagement with the operating bar (as shown in Fig. 3) so that if the trigger is pulled before the hand pressure on the lever-extension is relieved, the sear is tripped out of bent and the pistol is 40 discharged.

The housing may be pivoted between the cheeks or rear extensions *b*¹ of the body in any convenient manner, but in the arrangement shown in the drawings, this is effected 45 by the pin *e*² which serves as the sear pivot, and whose ends are extended beyond the sides of the sear, so that they will pass respectively through the opposite sides of the said housing and engage in bearings *b*² in 50 the said cheeks *b*¹.

Preferably, I provide the sear with a depending tail or extension *e*³ the back edge of which, when the parts are in the "safety" position and the hammer is cocked, has a 55 solid bearing or abutment against a part of the main frame or body of the pistol so that it is incapable of any movement in the direction in which it has to be tilted to effect the disengagement of the nose of said sear 60 from the hammer bent. Further, and as an additional precaution, I may form the underside of the breech-slide *i* of the pistol with a rib *z*¹ whose opposite sides lie upon the sear when the slide is closed and the 65 parts are in the "safety" positions, and

thereby keep the nose of the said sear jammed in the hammer bent whereas when the said parts are transferred to the firing positions by the grip of the hand on the lever extension of the sear-housing, the sear-extension is lifted away from its abutment on the frame and the sear nose is depressed clear of the bottom of the breech-slide (see Fig. 1) so that the sear may make its angular hammer-disengaging movement when 75 acted upon the sear-operating bar on the trigger being pulled.

Instead of the sear-housing being pivoted to make an angular movement for taking the sear into and out of relation with the trigger, the said housing may be feathered or dovetailed to the body so that the sear may have a sliding movement relative to the main frame and trigger.

Figs. 10, 11 and 12 are views showing how 85 the safety housing and rear part of the frame may be constructed according to this modification; the said housing *d* being formed with the feathers of guide ribs *d*¹ which corresponding grooves or featherways 90 *b*⁴ are formed on the inner sides of the side walls at the rear of the frame. The sliding part carries the hammer and sear and their springs as in the previously described arrangement, and when in position, it is influenced by a suitably applied spring or springs 95 acting to automatically place the parts of the firing mechanism at safe as soon as the hand grip on the handle is relieved, while the depending part *d*¹ is arranged to fit into 100 the back of the said handle for bringing up the said parts to the firing position when the pistol is grasped as already described.

When the hammer of the firing mechanism is actuated by a spring of the spiral 105 type, this spring may be also utilized to give the movement to the housing for positioning the parts at "safety." One such arrangement is shown in Fig. 13, wherein the spring *f*¹ is arranged within a suitable 110 hole or recess in the housing and its opposite ends are made to work against plungers or small slides *f*², *f*³, the former of which is adapted to transmit the effort of the spring to the hammer, while the latter may be arranged to bear against the frame or some other relatively stationary part at a point below the housing fulcrum, or at such other suitable point, as will insure that the effort 115 of the said spring shall tend to place the housing and parts that are mounted thereon in the "safety" position.

In the particular arrangement shown in Fig. 13, however, the hammer-spring plunger *f*³, instead of having a bearing 120 against the frame, is arranged so that it is utilized as a magazine latch; the same being formed with a spheroidal end which extends through a suitable opening in the front of 125 the housing and is adapted to engage with a 130

suitable recess j^1 in the back of the detachable magazine j on the parts being brought to the firing positions by the act of gripping the pistol in the hand, whereas when the 5 hand-grip is relieved, the rearward movement which the sear-housing makes on the expansion of the hammer and spring, takes the said latching end of the plunger out of engagement with the magazine and leaves 0 the latter free to be withdrawn.

Figs. 14 and 15 show another arrangement in which a magazine latch is mounted in the lever extension of the housing and is made to positively engage the magazine 5 when the pistol is gripped for firing, but has only a frictional engagement with the magazine when the parts of the special mechanism are in the "safety" positions. In the construction shown, the front of the 0 lever extension d^1 is chambered out to form a seating k^1 for a spherical ended latch-plunger k^2 and spring k^3 . The plunger itself is hollow and incloses the spring whose rearward end bears against the back of the 5 seating while its forward end bears against the plunger. Normally or when the parts are in the "safety" position as shown in Fig. 14 the spring forces the plunger out of its seating to such a distance that it can 0 engage with the back of the magazine and frictionally hold the latter in place so that there can be no danger of the said magazine dropping out of the chamber in the handle. The plunger is, however, made of such a 5 length that when the housing is moved forward to the firing position, its inner end will bottom against, or take a solid abutment on, the inner end of the seating as shown in Fig. 15; that is to say, it will become practically a solid part of the housing so that the hand pressure on the housing-lever will serve to keep the latching end of the plunger in positive engagement with the magazine and absolutely lock the latter to the frame of 5 the arm so long as the firing grip is maintained on the handle and lever extension of the housing.

Instead of a sliding plunger, I may use any other latch arrangement which is normally spring engaged with the magazine so as to provide a frictional fastening and yet enable said magazine to be withdrawn when required, but which has a rigid or dead bearing against same part of the sear-housing or its lever on the latter being brought up to the "firing" position.

The application of the improvements to automatic rifles differs in no essential respect from its application to pistols as herein described; the housing in which the hammer and sear are mounted being arranged in the stock of the arm, at the back of the magazine chamber, and provided with a lever-like extension which is arranged so that it 5 will be acted upon by the hand of the shooter

when the stock is grasped prior to firing and will thereby move the housing or supplementary frame and take the various parts of the firing mechanism into operative relationship with one another.

70

I claim—

1. In a fire arm, the combination of a main frame, a safety housing movable with respect to the frame, and firing mechanism comprising a hammer and sear carried by 75 said housing, and a trigger and sear-tripping bar carried by the main frame, said sear being carried into operative relation with the said tripping-bar when the housing is moved in one direction.

80

2. In a fire arm, the combination of a frame carrying a trigger and a sear-tripping bar, a housing movable relatively to the frame and arranged at the rear of the handle or grip thereof, a spring for normally holding the housing in inoperative position, and a hammer and sear carried by said housing, the releasing part of the sear being in substantial alinement with the tripping bar but normally inoperative thereby, a movement of said housing carrying the sear into coöperative relation with the tripping bar.

85

3. In a fire arm, the combination of a frame provided with a handle or grip, a trigger and sear-tripping bar mounted in 95 the frame, a safety housing movably mounted with respect to the handle or grip and having a spring for normally holding it in retracted position, a hammer, a sear coöperative with the hammer and arranged to be 100 moved into operative and inoperative relation with respect to the tripping bar by movements of the safety housing, and means coöperative with the sear for locking the same from tripping movement while the 105 housing is in retracted position.

90

4. In a fire arm, the combination of a frame having a handle or grip, a trigger and sear-tripping bar carried by the frame, a safety housing pivoted to the frame in 110 rear of the handle or grip, a hammer, a sear coöperative with the hammer and carried by the safety housing, said sear having an extension arranged to be carried into coöperative relation with the sear-tripping bar 115 when the housing is pressed toward the handle, the frame having a portion adapted to receive said extension on the sear and thereby hold the latter permanently in bent position while the safety housing is retracted.

120

5. In a fire arm, the combination of a frame having a handle or grip, a reciprocating breech slide thereon, a trigger and sear-tripping bar mounted in the frame, a safety housing movably mounted with respect to 125 the handle or grip, a hammer, and a sear coöperative with the hammer and arranged to be carried into operative and inoperative relation with the tripping bar by movements of said housing, said sear being carried into 130

locked engagement with the breech slide to prevent releasing of the sear when the safety housing is in retracted position.

6. In a fire arm, the combination of a frame, trigger mechanism carried thereby, a safety housing pivoted to the frame in rear of the grip thereon, a hammer mounted on a common pivot with said housing, and a sear coöperative with the hammer and carried by
5 the housing into operative and inoperative

position with respect to the trigger mechanism on the frame.

In testimony whereof I have hereunto set my hand in presence of two subscribing witnesses.

WILLIAM JOHN WHITING.
